HOUSING FOR ALARMS AND THE LIKE

James P. Wang and David I. Wolsk, Lexington, Ky., assignors to Wolsk Associates, Ltd., Lexington, Ky.

Filed Sept. 29, 1975, Ser. No. 617,691

Term of patent 14 years

Int. Cl. D10—05

U.S. Cl. D10—106

FIG. 3

FIG. 1 is a front elevational view of a housing for alarms and the like showing the new design.

FIG. 2 is a right side elevational view of the housing for alarms and the like of FIG. 1 with the other side (not shown) of the housing being identical to FIG. 2.

FIG. 3 is a rear elevational view of the housing for alarms and the like of FIG. 1.

We claim:

The ornamental design for a housing for alarms and the like, substantially as shown and described.
